UNITED STATES PATENT OFFICE.

VICTOR E. THELIN, OF CHICAGO, ILLINOIS.

AUTOMATIC SUBSTATION.

Application filed June 25, 1921. Serial No. 430,392.

To all whom it may concern:

Be it known that I, VICTOR E. THELIN, a citizen of the United States of America, and a resident of Chicago, county of Cook, and State of Illinois, have invented certain new and useful Improvements in Automatic Substations, of which the following is a specification.

This invention relates to electrical power distribution systems and especially to automatic substation and apparatus therefor. The desirability of providing automatic substations, has been generally recognized, and a great deal of attention has been devoted thereto.

Various automatic devices have been developed for embodiment and use in substations, but so far as I am aware, no one else has ever yet succeeded in rendering a substation of the character referred to entirely automatic with as few parts as the one described herewith.

My invention is especially adapted for use in power and traction systems having substations fed from high tension alternating current transmission lines, and delivering direct current to the distribution system.

The main objects of my invention are to provide an improved and simplified system of control apparatus adapted to render a substation or its equivalent entirely automatic; to provide such a system adapted both to start up and shut down a substation without the presence or assistance of any attendant whatever; to provide such a system adapted to be responsive to any predetermined governing factor, as for instance a time clock, the line voltage, current load, or any desired combination of these or other factors; to also provide in such a system automatic means to insure correct polarity on the secondary or direct current side of the rotary converter before it is connected to the distribution system; and to provide and correlate the necessary apparatus, mechanisms and appliances for such a system adapted to effect the control desired, and to provide a better and more efficient arrangement of apparatus, so as to simplify the operation and render same more dependable.

An illustrative embodiment of this invention is shown in the accompanying drawings, in which—

Figure 1 is a conventional diagram showing the sequence of steps in the operation of starting up the substation.

Fig. 2 is a circuit diagram of the substation as a whole.

Fig. 3 is a side elevation of the magneto-motor driven polarized relay.

Fig. 4 is an end view of the device, shown in Fig. 3, as viewed from the right.

Fig. 5 is a plan of said device of Fig. 3.

Fig. 6 is an enlarged end view of the switch elements of said device of Fig. 3.

Fig. 7 is a conventional circuit diagram of said relay.

Fig. 8 is a front elevation of the combination automatic field control and change-over switch.

Fig. 9 is an end view of said change-over switch as viewed from the left of Fig. 8.

Fig. 10 is a cross section on the line A—A of Fig. 8.

Fig. 11 is a cross section on the line B—B of Fig. 8.

Fig. 12 is a cross section on the line C—C of Fig. 8.

The automatic substation equipment here shown and described in detail, represents mainly a simplified form of apparatus for automatically controlling the operation of electrical substation machines such as converters, motor generators and the like. In designing this equipment, I have endeavored to duplicate, by means of a few reliable pieces of electrical apparatus, the various operations that an attendant ordinarily performs manually in starting up a substation machine, but each individual piece of apparatus is so interlocked with the rest of the apparatus that each operation must have been properly and effectively carried through before the next operation can take place.

In order to convey at once a concise idea of the nature and subject matter of my invention, I will here state that the method of operation for my improved system, briefly described, for starting a rotary converter, reference being had to the drawings and especially Figure 1, is as follows:

1st. Contact making time clock 1 operates.

2nd. Master control relay 2 operates which in turn,—

3rd. Closes starting contactor 3, which

starts the rotary converter on low voltage on "half tap."

4th. Magnetomotor driven polarized relay 4 then operates,

5th. Closing the combination field control and automatic change-over switch 5, which in turn,

6th. Opens the starting contactor 3 and closes the running contractor 6, to supply full voltage to the converter,

7th. After which field circuit time limit relay 7 closes, and the

8th. Automatic reclosing circuit breaker 8 closes, picking up the station load.

15th. In case it should be desired to control the substation manually from a remote point, a remote control relay 10 is used as shown at the right of the clock on Fig. 2, and this relay is connected to a remote switch 11 which may be mounted in a central power station.

In case the rotary comes up with reversed polarity, the polarized relay 4 shuts the station down and the above described first four steps of the operation are repeated until the rotary comes up positive, after which the regular full sequence of operation is carried through, as will be more fully explained.

30th. The principal parts of the above mentioned apparatus and for which patent protection is especially desired are the magnetomotor driven polarized relay 4 and the combination automatic field control and change over switch 5. The rest of the equipment mentioned, as well as the protective devices, is mainly standard electrical apparatus some parts of which have been slightly altered for various reasons as hereinafter explained.

A detailed description of the different parts of the apparatus shown is now given which parts are described in the numerical order in which they are numbered.

45th. *No. 1.—Contact making time clock.*

This unit of apparatus includes an electric switch that is opened or closed at some predetermined time by means of an ordinary spring wound time clock, all of the parts of this apparatus being self contained in a weatherproof iron case. This clock is used both when the station is running as a straight automatic substation and as a semi-automatic substation.

No. 2.—Master control relay.

This is a standard alternating current contactor switch equipped with contact fingers and interlocks and supplies current to the various operating circuits.

No. 3.—Starting contactor.

This apparatus is a standard alternating

current solenoid operated multi-pole contactor switch and is used to furnish current at a reduced voltage from the power transformer for the purpose of starting the rotary converter.

No. 4.—Magnetomotor driven polarized relay.

This device, which is a new and specially built piece of apparatus, consists of two principal parts, namely, a permanent magnet low voltage direct current motor and a single pole knife blade switch mounted on a shaft which operates as a double throw switch, when connected to said motor, by means of a specially designed centrifugal friction-clutch. The relay motor armature is connected between the positive machine lead and ground with the necessary resistance in the circuit. This resistance is so adjusted that the relay motor does not begin to rotate until the direct voltage on the machine (converter) has reached the maximum voltage obtained when starting up on a reduced A. C. pressure. Due to the fact that the relay motor has permanent magnet fields the direction of the rotation of its armature is dependent on the polarity of the rotary converter. When the relay armature reaches the required speed the centrifugal clutch takes hold, thus rotating the shaft of the oscillating relay switch and thereby operating switch 5 and closing the circuits of the various devices controlled by same.

No. 5.—Combination automatic field control and change over switch.

This device also is a specially built piece of apparatus. This switch and the polarized relay 4 are the principal parts of the automatic equipment, and are the means that enable the automatic control to operate with so few parts as it does. This is primarily due to the fact that switch 5 is a combination switch that performs various operations and controls several circuits simultaneously, due to the fact that the various parts are all mounted on the same shaft. This device changes the impressed alternating voltage on the rotary from a reduced potential to full potential and simultaneously changes the field from one-tenth to full field. It is also inter-connected with the rest of the station apparatus in such a way that the rotary will not start up again until said switch returns to the initial starting position, and being equipped with an air dash pot there is sufficient delay in the opening of said switch for all other apparatus inter-connected with same to have returned to its starting position, thus insuring a safe starting of the rotary.

The structural details of this combination switch 5, as well as those of polarized relay

4, above referred to, are described farther on where specific reference will be made to the drawings.

5 *No. 6.—Running contactor.*

This apparatus which applies full alternating potential to the rotary is a duplicate of starting contactor 3 and is both mechanically and electrically interconnected with 10 the latter so that neither can close until the other has opened.

15 *No. 7.—Field circuit time limit relay.*

This device is a standard inverse time 20 limit over load relay which is inserted in the shunt field circuit to prevent the rotary converter from going in on the direct current bus with a field current below that required for the safe operation of the equipment.

25 *No. 8.—Automatic reclosing circuit breaker.*

This apparatus, which is a standard automatic reclosing circuit breaker, connects the rotary converter to the station direct current 30 bus. In case this breaker opens due to a short circuit or heavy overload on any of the direct current feeders it will close automatically again after a certain time limit has elapsed.

35 *No. 9.—Self-correcting time limit relay.*

This is a standard time limit alternating potential relay. It is used for the purpose of shutting down the rotary in case same 40 does not pick up the station load after the normal time has elapsed for so doing. Whenever said relay 9 operates the regular sequence of operation for starting the rotary will then be carried through again, and in this way it is possible to correct 45 trouble caused by poor contacts, etc. Hence the name, "self-correcting relay".

50 *No. 10.—Remote control starting relay.*

55 This relay, which is energized with current sent from some remote point by means of pilot wires is used for the purpose of either starting or stopping the rotary at a time other than that at which the clock either starts or stops the rotary. It is also used in place of the clock in case the starting and stopping of the rotary is to be done from some remote point.

60 *No. 11.—Low voltage relay.*

This relay, which is connected between the substation feeder bus and ground, has a pair of interlocks that are connected in the control circuit running from time clock 65 #1 and master relay #2, and its purpose is to prevent the station from starting up when the clock operates, if the potential of the substation feeder bus is above a certain predetermined value. It is equipped with

a time limit device to prevent operation on 65 momentary fluctuations of voltage.

The various protective devices will now be described. They are numbered consecutively from 20 up.

70 *No. 20.—Low current relay.*

This instrument, which is a standard shunted type D. C. machine ammeter, is so arranged that when the current in the machine reaches some predetermined minimum value, the lower end of the pointer of the instrument opens the circuit to the operating coil of auxiliary low current relay 20^A causing the interlocks of the latter relay to open and shut the rotary down, provided time clock #1 has tripped open. Auxiliary low current relay #20^A is equipped with a time limit device, so as not to respond to momentary fluctuations in the load.

75 *No. 21.—Secondary control relay.*

This relay, which is a solenoid type potential relay is used as an auxiliary relay to reverse current relay 20 and to reverse power relay 22, because the contacts of these latter instruments are not capable of carrying heavy currents.

80 Relay 21 is used also as an auxiliary relay for the negative operation of polarized relay 4, and for time limit self correcting relay 9. Its trip fingers are in series with the operating coil of master control relay 2 causing the latter to open whenever the coil of the former is energized. Due to being interconnected with so many devices as just mentioned and being so closely related to master control relay 2, I call it the secondary control relay.

85 *No. 22.—Reverse power relay.*

This relay, which is an induction watt relay that operates on a reversal of power in the secondary leads of the power transformer is used for the purpose of preventing the rotary from being damaged from over speed in case of failure of the A. C. power supply. Its trip circuit energizes the lifting coil of secondary control relay 21 as 90 already mentioned above.

95 *No. 23.—Reverse phase relay.*

This relay is a standard reverse phase relay that operates to shut down the substation in case any of the three phases reverse or open up. This relay will also shut the station down in case abnormally low A. C. voltage should occur.

100 *No. 24.—Reverse phase auxiliary relay.*

105 This relay is a regular solenoid type of relay, which is used as an auxiliary relay to reverse phase relay 23.

No. 25.—Bearing thermostats.

These thermostats are mounted on the bearings of the rotary converter, and are used to protect same from becoming overheated.

No. 26.—Transformer thermostat.

This thermostat, which is a duplicate of the ones used on the bearings as above mentioned, is installed in the transformer for the purpose of protecting same from becoming overheated, due to overload.

No. 27.—Overspeed device.

15 This is a regular overspeed device, which is used for protecting the rotary converter from damage, due to speeding up from any one of various causes.

No. 28.—Oil circuit breaker trip relay.

This relay is a specially built piece of apparatus, which is used for the purpose of tripping the release catch on the handle 25 that controls the opening and closing oil switch, whenever thermostats 25 and 26, or speed limit device 27 operate. It is also interconnected with the oil circuit breaker control handle 29, so that in case the latter 30 opens, the core of relay 28 will drop causing the automatic reclosing circuit breaker to also open thereby making it impossible for the rotary converter to speed up, due to being fed with D. C. from the substation bus.

No. 29.—Oil circuit breaker control handle.

This is a standard control handle for a type "K" oil circuit breaker, which handle 40 is equipped with an interlock, so that when same opens, it will cause relay 28 to drop, as mentioned above, thereby opening the automatic reclosing circuit breaker on generator panel.

No. 30.—Reverse current relay.

This relay is a standard reverse current relay, and is adapted to open up the breaker whenever a reversal of current occurs on 50 same.

No. 32.—Substation operating battery.

This is a standard twenty cell operating storage battery, which is used to furnish power to certain pieces of apparatus, that would be inoperative in case they were supplied with power from the station bus which would be dead in case the entire D. C. feeder system were shut down.

No. 33.—Automatic reclosing feeder circuit breakers.

These breakers are standard automatic reclosing circuit breakers. They are used on 65 the feeders for the purpose of cutting same

off in case of trouble of any sort. They automatically reclose whenever the trouble has disappeared.

No. 34.—Sectionalizing relay.

This relay, which is of a simple solenoid type, is used to separate the ground circuit of the operating coil of the automatic reclosing circuit breaker 8 from that of the oil circuit breaker trip relay 28 whenever 75 the overspeed device 27 opens. If this were not provided for there would be a shunt path to ground around the overspeed device 27 by way of the operating coil of the oil circuit breaker trip relay 28 and storage 80 battery 32 which might prevent automatic reclosing circuit breaker 8 from opening.

No. 40.—Current transformer.

This is a standard current transformer 85 that is inserted on the low tension side of the power transformer for the purpose of furnishing current to the reverse power relay 22.

No. 41.—Potential transformers.

These are two standard 370 to 110 volt 90 transformers that are used for the purpose of furnishing polyphase potential to reverse phase relay 23. In case the power furnished to the high tension line is obtained from the central station by means of transformers that are Δ connected with a grounded neutral, it is possible to install a small transformer between one phase of the high tension line and ground for the purpose of furnishing current for operating starting contactor 3 and running contactor 6, and when the power supply on the high tension line is interrupted in case of trouble the contactors 100 will open up, in which case it is unnecessary to have reverse power relay 22.

Referring now to the more specific structural features involved, the magnetomotor driven polarized relay No. 4 is a combination of a permanent magnet motor 4', a centrifugal clutch 61 and a specially constructed electric switch 62 mounted on a shaft 63, which is rotated by said motor by means of said clutch 61 whenever the motor armature reaches a certain predetermined speed.

The main portion shown on the left of Fig. 3 is a standard permanent magnet ball bearing low voltage D. C. motor 4'. Being equipped with permanent magnet fields, its rotation is entirely dependent on the polarity of the impressed voltage, and in case this polarity is reversed, the motor will revolve in the opposite direction.

The centrifugal clutch 61, mounted directly on the shaft of the motor, includes springs 67 set radially in pairs on the ends of which are several weights 68, which move further from the axial center, due to cen-

trifugal action, whenever the motor is speed-
ing up. The left hand collar 69 supports
one end of springs 67 and is fastened rigidly
to the motor shaft by means of pin A. The
right hand collar 70 supports the opposite
ends of said springs, and being loose on the
shaft moves inward as the weights move out-
wardly. This movable collar has a thin
brass disc 71 mounted thereon and when
the motor has reached a certain predeter-
mined speed, contact is made between this
disc and the two leather friction discs 72.
This causes the switch shaft 63 to rotate,
thereby making contact on fingers B and C
or D and E, depending on the direction of
rotation of the armature. It should be
noted that the supporting yoke 74 that holds
the two springs 75 to which the friction
disks 72 are fastened, is pivoted at pin P
thus allowing for any small variation in the
turning of disc 71. The yoke support 74
is threaded on to the switch shaft 63 and is
held in place by means of a locknut 77, so
that the gap between the discs 72 and the
disc 71 can be adjusted, and thus allow a
greater or less speed in the motor before
the clutch takes hold.

The relay switch 62 comprises the shaft
63 which rotates in bearings 78, a block of
fibre 79 clamped on this shaft, two pieces
of spring bronze 80 on the ends of which
are two copper strips F and G. When the
shaft is rotated by means of the centrifugal
clutch, these strips of copper close the cir-
cuit across contact fingers B-C or D-E,
which are mounted on a fibre base. These
contact fingers are made up of a thin flexi-
ble piece of spring bronze and a rigid piece
of copper, the flexible piece of spring bronze
acting as an arcing tip, due to the fact that
the movable copper strip touches this first
when making contact, and leaves it last
when breaking the contact, thus insuring
a clean surface at all times on the rigid
pieces of copper. The method of operation
is shown by Fig. 6. The copper strips F
and G that make contact across fingers B
and C or D and E are mounted on a piece
of spring bronze so as to make perfect con-
tact with the rigid copper fingers B and C
in case the latter do not line up perfectly.
When the speed of the motor is reduced so
that the leather discs leave the disc 71 at
the clutch, the weight W restores the switch
to the neutral position, as shown on at-
tached blue print.

The weight W is used instead of springs
for restoring the switch to its neutral po-
sition, for it was found by experiments that
when using springs the switch blade would
rebound sufficiently to make contact on the
opposite clips. This was due to the fact
that when the clutch let go the springs were
under maximum tension and as the switch
reached its neutral position the springs were

at a minimum tension and the switch there-
fore not only passed the neutral position
but at times continued to move so far as to
make contact on the fingers on the opposite
side of the switch. The use of a weight
suspended on the lower end of the switch
eliminated the rebound due to the fact that
as the switch moves from either side to the
neutral position the weight moves down-
ward as well as sideways and when the
switch passes the neutral position the
weight has to be stopped in its downward
movement and started upward against grav-
ity, which prevents the switch from moving
very far past center. The electrical
connections of the polarized relay are shown
by Fig. 7.

The combination automatic field control
and change over switch 5 is a combination
of several switches which are mounted on a
common base 73 and so arranged and in-
terconnected as to obtain either simultaneous
or interlocked operation of the various cir-
cuits and pieces of apparatus that are con-
trolled by this switch as explained in detail
later on. The apparatus consists primarily
of seven switches or fingers mounted on a
rotary shaft 74 which is rotated by a sole-
noid 75 equipped with an air dash pot 76.
Three of these switches, namely, #1, #5,
and #7 are fastened rigidly to said shaft,
while switch #4 is free to move a certain
distance being controlled by a spring 77.
Switches #2, #3, and #6 on the other
hand are what might be called quick make
and break knife edge switches that are op-
erated by a piece of fibre mounted on said
shaft.

A more detailed description of the con-
struction, function and operation of the
parts of said switch 5 may be stated as fol-
lows:

Switches #1 and #7, which are identi-
cal both as to construction and function as
well as operation, are each constructed of
fibre cut in the shape of two spokes and the
hub of a wheel as can be seen in Fig. 9. At
the outer end or what would correspond to
the rim end of each of the spokes, is mount-
ed a flexible carbon and copper make and
break contact finger 79 which makes con-
tact with a similarly constructed finger 80
that is mounted on the switchboard. Fin-
ger #1 is connected to the positive end of
the shunt field winding and finger #7 is
connected to the negative end. The copper
and carbon contacts at both ends of the
same finger are tied together and to a com-
mon binding post 81 by means of flexible
leads 82. The stationary copper and car-
bon switchboard clips that engage the lower
clips on fingers #1 and #7 are connected
to the station bus through resistance of the
required value to give one tenth the normal
full strength on the shunt field while the

upper stationary clips that make contact with the upper clips on fingers #1 and #7 are connected to the positive and negative leads of the rotary converter. It is evident therefore that when the combination switch is closed by energizing the solenoid 75 the shunt field is changed from one-tenth field strength, fed from the station bus, to full field strength, fed from the rotary itself. These field fingers are so constructed, that, when closing, the carbons make contact first and the flexible copper fingers last and when opening the copper fingers break first and the carbon last causing latter fingers to receive all the arcing, thus insuring a clean contact on the main copper contacts. The copper fingers also make a wiping contact thereby making sure of greater reliability in operation. Said solenoid 75 is equipped with an air dash pot 76 so as to cause the combination switch to open slowly, thereby dissipating the energy of the field in the arc. The insulation of the field is further protected from a break down by finger #5 which acts as a discharge switch for the field as follows. The two leads of the shunt field in addition to being connected to switches #1 and #7 are also connected to the opposite ends of switch #5 and when the switches move from either the lower contacts to the upper contacts or vice versa, switch #5 makes contact with two double sets of switchboard clips that are connected to a low resistance thereby causing the field to discharge through this resistance.

Switch #4 is very similar in construction and shape to switches #1 and #7, the principal difference being that the latter two are fastened rigidly to the rotating shaft while the former is not. This switch #4 which might be called a "sealing in" switch, is so constructed that it will make contact with the clip 86 on the switch board when the shaft has rotated a small portion only of its total travel, and said switch will remain stationary while the shaft completes its travel during which time pin P moves upward in the slot in the middle of the switch while the switch is held tight against its clip by means of coiled spring 77. When the combination switch opens again the shaft rotates in the opposite direction and when the pin P reaches the bottom of the slot in the finger switch #4 will open again against the action of the spring 77.

Switches #2, #3 and #6 are quick acting knife edge make and break switches which are especially designed so as to provide a certain time delay during which other switches on the same shaft make or break their circuit and when the former finally operate they do so with out a second's delay in their action. Switches #2 and #3 are constructed as follows: A piece of fiber 88 cut in the shape of capital letter H is

equipped at the lower end with case hardened knife edges 89 which rest in the bottom edge of a V-shaped metal groove 90 while the two upper arms of the H are equipped with copper fingers 91 that rest against two independent copper clips 92 when the switch is in the open position and make contact with two other independent clips on the switchboard when the switch is in the closed position. The switches are held tight against the forward stops or clips by means of a coiled spring 93 which is fastened between the center part of the H switch 2-3 and the top of a short fibre finger that is fastened rigidly to the rotating shaft. When the shaft revolves or rotates the top of the fibre finger moves nearer and nearer the knife edges on the H switch and the tension on the spring becomes less and less and when the finger has passed to a point to the other side of a line drawn through the center of the revolving shaft and the knife edges, the H switch snaps over to the other position quickly and as the top of the fiber finger moves more and more toward the switchboard, the tension on the spring becomes greater thus insuring a perfect contact between the various electrical parts. When the combination switch opens again the operation is just the reverse of that mentioned above.

Switch #6 is also a quick break knife edge switch but differs from #2 and #3 in that it is a single pole switch whereas the combination of #2 and #3 form a double pole switch. Switch #6 is equipped with an air bellows time limit device 95 which further increases the time of operation of the switch as follows: The fibre finger on this switch is constructed like that on switch #4 in that it is not fastened rigidly to the shaft but is controlled by a spring 96 that is coiled around and fastened to the shaft. When the shaft rotates the tension in the spring tends to move the finger, but its movement is retarded by the back pressure from the air bellows in the time limit device. The time limit device is in operation only when the switch is closing and there is, therefore, no delay when same is opening. The fingers that carry the electrical current are made up of two parts and in some cases three parts as follows: In case there is considerable arcing when the circuit is broken the switch finger is equipped with a carbon arcing tip 97 which is the last part of the switch to open and, therefore, prevents the burning of the copper fingers. The copper part of the finger is made up of two parts, namely, the secondary break 98 and the main finger 99, the latter of which is designed to carry the current. In case the carbon tips just mentioned above should fail to function properly the arc would be broken on the secondary break and still

leave the main contact finger in good condition for carrying the current. Where the current is not very great the carbon arcing tip is not needed.

5 *Operation of automatic equipment.*

The position of the various parts of the automatic equipment in case there is no trouble existing on the A. C. high tension line when the station is ready to start up is as follows:

10 The oil circuit breaker 29, the trip relay 28, the A. C. operating bus switch 51 and the D. C. operating bus switch 52 are closed, and change over switches 56, 57 and 58 are in the downward position. The circuit for relay 28 is as follows: from storage battery operating bus S through S¹, relay 28, N²⁷, lower right blade of change over switch 58, N²⁸, interlock on oil circuit breaker handle 29, N²⁹, contacts of sectionalizing relay 34, N³⁰, N³¹, coil of sectionalizing relay 34, N²², transformer thermostat 26, N²³, bearing thermostat 25, N²⁴, bearing thermostat 25, N²⁵, speed limit 27 and N²⁶ to negative operating bus. Time clock 1, master control relay 2, starting contactor 3, running contactor 6 and automatic reclosing circuit breaker 8 are open, but main D. C. switch in 15 rotary positive lead is closed and various protective devices are either open or in a neutral position. The polarized relay 4 is in the neutral position and combination automatic change over switch 5 is in the open or 20 starting position. The shunt field of the rotary is excited with current from the station bus which current is approximately .5 amp. or one-tenth of the normal exciting current. The circuit to the shunt field S. F. is as follows: from the substation main positive bus through P²⁰, left hand lower blade of switch 56, P²¹, one-tenth field resistance, P²², lower half of finger B of combination switch 5, P²³, middle blade, lower middle clip, jumper 25 and upper right hand clip of change over switch 57, P²⁴, upper left hand clip of shunt field break up switch. Then through shunt filed to N¹, lower left hand clip of change over switch 57, N², lower half of finger A 30 and lower left hand clip of combination change over switch 5 and N³ to negative operating bus.

Starting.

35 When contact making time clock 1 operates, a circuit is completed to master control relay 2 from A phase operating bus, A¹, middle lower clip of changer over switch 58, upper part of time clock switch, lower left hand clip of change over switch 58, A², interlock on secondary control relay 21, A³, A⁴, quick break finger "G" of combination automatic switch 5, A⁵, A⁶, upper interlock of reverse phase auxiliary relay 24, A⁷, master control relay resistance 2^r, operating coil

of master control relay 2, B², B¹, to B phase operating bus.

In case the rotary is to be started by means of remote control instead of by means of clock 1 the circuits are completed through 70 the interlocks of remote control relay 10 instead of through the interlock of clock 1.

When master control relay 2 closes, a circuit is made to starting contactor 3 as follows: from B phase operating bus through 75 B¹, B³, finger 2 of master control relay 2, B⁴, quick break finger F of combination automatic change over switch 5, B⁵, operating coil of starting contactor 3, C³, C² and C¹ to C phase operating bus. The closing of 80 starting contactor 3 connects the rotary to the half tap of the power transformer (185 volts) and the rotary comes up to synchronous speed in approximately 20-25 seconds.

When the starting contactor 3 closed, a 85 circuit was made through its lower interlock to the armature of magnetomotor driven polarized relay 4 as follows: from positive operating bus P through P¹, armature of polarized relay 4 and resistance 4^r, N⁵, lower 90 interlocks on starting contactor 3 and N⁶ to negative operating bus N. During the time that the rotary starts up there is A. C. potential generated across the D. C. leads of 95 the machine and as the speed becomes greater the frequency of this A. C. current decreases until finally the rotary locks into step with the frequency of the A. C. high tension supply line and the rotary assumes a definite polarity but in this case due to the fact that 100 the field is excited from an independent external source of power, namely, the station D. C. positive bus, the rotary comes up with the correct polarity, that is to say, the lead going to the station bus being positive. 105

When the rotary first starts the high frequency current has no effect on the motor of polarized relay 4, but as the frequency decreases the armature oscillates more and more, and, due to the fact that the motor has a permanent magnet field, the rotation is dependent on the polarity of the current impressed across its armature and when the rotary finally comes up to synchronous speed with correct polarity it will rotate in the correct direction and continue the sequence of operation. A resistance is inserted in 110 series with the armature so that it will not start to rotate until the voltage is somewhere near the full value to be reached while rotary is running on the half tap of the transformer. When polarized relay operates in 115 the positive direction it makes a circuit across positive clips D and E to the operating coil of combination automatic field control and change over switch 5 as follows:

from positive operating bus P through P², P³ to positive clip D, finger G to positive clip E, P⁴ to operating coil of combination change over switch 5, N⁸, N⁹, finger E of 120

125

130

switch 5, N^{10} to finger 5 of master control relay 2 and then through N^{11} to negative operating bus N. When combination change over switch 5 closes, there are many changes that take place, but those things which have to do with completing the operation of the switch itself will be described first. As already explained under the detailed description of the construction of this switch 10 finger D is operated by means of a spring when closing and after having made contact with its clip on the switchboard, the shaft continues to rotate due to the fact that the finger is loose on the shaft. When 15 the switch is in the open position there is very little space between finger D, and the clip on the switchboard and contact is made before the shaft has moved very far, and before any of the other fingers or switches 20 have operated. Finger D just mentioned is a holding in or sealing in finger and it together with wire P^5 forms a shunt circuit around contact clips D and E of polarized relay 4 when the latter opens as explained 25 later on. In order that the coil of combination change over switch 5 will have plenty of power when closing the switch, the resistance 30 in series with the coil is shunted by quick break switch E. This latter switch is equipped with an air bellows time limit which prevents the short circuit from being removed from around the resistance until the core of the solenoid coil will have completed its travel and sealed in perfectly. 35 Due to being equipped with a time limit, finger E is the last switch or finger on combination switch 5 to operate. When combination switch 5 moves from the open to the closed position, fingers A and B break the 40 one-tenth field circuit on the lower clips and transfer the field to full voltage as follows: from rotary positive lead through P^{16} to field rheostat 44, P^{17} , right hand blade of change over switch 57 to bottom right 45 hand clip of same, P^{18} to coil of field circuit time limit relay 7, P^{19} , upper right hand clip and finger B of combination switch 5, P^{20} , middle blade, lower clip, jumper and upper right clip of change 50 over switch 57, P^{24} , shunt field of rotary, N^1 , left hand blade and lower left hand clip of change over switch 57, N^2 , finger A and upper left hand clip of combination switch 5 and then through N^4 to 55 negative operating bus N. During the time that combination switch 5 moves from the open to the closed position contact is made by finger C with its clips thus connecting the two ends of the shunt field across 60 a low resistance and discharging the field. As a precaution against a high induced voltage in case an open circuit should develop in the wiring of the one-tenth field circuit a resistance of approximately 750 65 ohms is connected directly across the ex- treme lower left and right hand clips of combination switch 5 and when fingers A and B are in the down position the resistance is actually tied across the field itself. The only switches or fingers on combination 70 switch 5, the operations of which have not been mentioned as yet, are F and G, and with the exception of finger E, are the last ones to operate. As already noted under construction details, these two switches 75 control independent circuits but are mechanically fastened together in order to get simultaneous operation. When switches A and B have transferred the shunt field from the station bus to the lead of the rotary and so made it self-excited, switch F operates and changes the rotary from the half tap to the full tap by opening starting contactor 3 and closing running contactor 6, and the circuit for making this change is as follows: 80 from B phase operating bus through B^1 , B^3 , finger 2 of master control relay, B^4 , finger F of combination switch 5, B^6 , operating coil of running contactor 6, C^4 , upper interlocks of starting contactor 3, C^2 and C^1 to C phase operating bus. When starting contactor 3 opens, its lower interlocks open the circuit between N^5 and N^6 which shuts down polarized relay 4, as its services are no longer needed. It should be noted that the circuit that controls the operation of running contactor 6 as just mentioned above, is so interlocked with starting contactor 3 that the latter has to be open before the former can be closed and the circuit for operating running contactor 6, therefore, is not completed when finger F of combination switch 5 operates until contactor 3 opens. In addition to being electrically interlocked, 90 starting contactor 3 and running contactor 6 are also mechanically interlocked so it is impossible to close both simultaneously, which would result in a short circuit between the half tap and the full tap on the transformer in case same did happen. Finger G of combination switch 5, which finger is in parallel with finger 4 of master control relay 2, is installed as a safety interlock in the operating coil circuit of master control relay 2 so that the latter can not 95 close again at any time until combination change over switch 5 has returned to the open position and has thereby restored all of the automatic equipment to the normal position for starting the station again. If this interlock were not provided, master control relay would close as soon as secondary control relay 21 dropped regardless as to whether combination change over 100 switch were still in the closed position, or the open or normal position for starting the station. If switch 5 were in the closed position when master control relay 2 closed again the rotary would be connected across 105 the full potential of the transformers with 110 115 120 125 130

full field which would result in serious damage to the machine. When finger G on switch 5 opened, the circuit to the operating coil of master relay 2, instead of going by way of A⁴, finger G of combination switch 5 and A⁵ goes by way of A⁸, finger 4 of master relay 2 and A⁹, which latter shunt circuit was made alive when master relay 2 closed as noted in early part of this report under description of operation. The details of the operation of the various parts of combination switch 5 are now complete and the rotary is now running at normal speed with full potential of the correct polarity and ready to pick up the station load. As already noted, the circuit from finger B of switch 5 to the shunt field passed through the operating coil of field circuit time limit relay 7 and if the current in the field is up to the required value the relay will close its contacts after a certain time has elapsed, which time limit is provided to enable the rotary to build up to its full potential. When relay 7 closes its contacts, a circuit is made to generator breaker 8, which is an automatic reclosing circuit breaker, as follows: from positive lead of rotary converter through P²⁴, interlocks of reverse current relay 30, P²⁹, operating coil of circuit breaker 8, N¹³, middle blade and lower middle clip of change over switch 56, N¹⁴, contact clips of field circuit time limit relay 7, N¹⁵, finger 3 of master control relay 2, N¹⁶, interlocks on running contactor 6, N¹⁷ and 18, contact clips of oil circuit breaker trip relay 28, N¹⁹, time clock 1, N²⁰, N²¹, coil of sectionalizing relay 34 and so on through thermostats and speed limit to negative operating bus. The closing of the breaker completes the cycle of operation of starting the rotary and picking up the station load, which operation is completed in approximately 40-50 seconds.

There is one finger or switch blade on master control relay 2, of which no mention has been made as yet in connection with the starting of the station, and that is finger 1 which controls the operation of self-correcting time limit relay 9. While this piece of apparatus is a protective device in that it has to do directly with the starting up of the station, or rather the failure of the station in starting, and, therefore, it no doubt would be best to describe the operation of same at this time. This relay which has a time limit that can be set from a few seconds to several minutes is so connected that in case generator breaker 8 did not close inside of the setting of the time limit of self-correcting relay 9, the contacts of the latter relay would close, thereby completing a circuit to secondary control relay 21, which would cause master control relay 2 to open. This in turn would open running contactor 6 which would cut off the A, C supply to

the rotary causing same to gradually shut down. Combination switch 5, being connected directly across the positive operating bus through holding finger D, which circuit is not interlocked through master control relay 2 in any way, would stay closed until the voltage on operating bus P dropped to a value below that at which the operating coil of combination switch 5 will stay closed after which same will open up and thereby close circuit to operating coil of master control relay 2 through finger G of switch 5. The regular sequence of operation of starting the rotary, as already explained in detail, would then be carried through again and the trouble that prevented the operation from being completed before (which might have been caused by poor contact, sticking of relay, etc.) might be overcome and the rotary would then pick up the load in say 40-45 seconds. In case the trouble were not remedied the first time, relay 9 would shut the station down again and continue to do so until the trouble were remedied if same could be remedied. It is a well-known fact that no matter what piece of apparatus man makes, that out of say a few thousand operations, there will be some hitch somewhere that will result in a certain percentage of failure which fact does not mean, however, that the apparatus will not work at all. In the automatic substation apparatus shown in the drawings, each operation of the apparatus is so interlocked that the failure of any part of same to function properly will prevent the sequence of operation to be carried further and in case of trouble on any part of same, the sequence of operation would be carried through to this point and no further. If the trouble, however, is a temporary one, such as poor contact, sticking of some part of the apparatus, etc., the addition of relay 9 to the automatic equipment gives same a chance to start over again and possibly overcome this trouble. If for some reason the rotary came up with its polarity reversed, the armature of polarized relay 4 will rotate in the opposite or negative direction from that above-mentioned, thereby closing the gap across contacts B and C by means of finger F, and making a circuit to secondary control relay 21 as follows: from positive operating bus P through P² to negative contact clip B, oscillating switch finger F, negative clip G, P⁶, P⁸, section tap on secondary control relay resistance 21^r, operating coil of secondary control relay 21 and N⁷, to negative operating bus N. Relay 21 and its resistance 21^r, are wound for 600 volt service and inasmuch as the rotary is generating half voltage, i. e., 300 volt, a section only of resistance 21^r is used by making a tap connection as above-mentioned, and positive operation of relay 21 is thus assured. When relay 21 operates it opens the circuit to the

operating coil of master control relay 2, causing same to open, which in turn opens starting contactor 3, thereby cutting off the power from the rotary and causing same to slow down. When starting contactor 3 opens, the circuit to the motor of polarized relay is broken on account of the lower interlocks of contactor 3 opening up and the motor of polarized relay 4 therefore would slow down. This would in turn open the circuit across negative clips B and C of polarized relay 4, and secondary control relay 21 would drop again, thereby closing the circuit to master control relay 2, which would close starting contactor 3, and rotary would be connected again to the half tap of the transformer. All of the operations would require a few seconds of time only, and the polarity of the rotary would not be corrected, as the rotary would not have sufficient time to drop out of step and slip a pole as it is called. This trouble is overcome, however, as follows: When core of secondary control relay 21 is lifted a contact is made across two fingers in the relay, thereby completing a sealing in circuit as follows: from positive operating bus P through P¹⁵, holding in fingers of relay 21, P¹⁴, resistance 21', operating coil of relay 21 and N', to negative operating bus. The coil of relay 21 is then connected directly across the rotary armature, and its core will stay up until the rotary has slowed down so that the voltage is not more than 25-50 volts. This allows sufficient time for the field to die down and when the rotary starts up again it will have a fair chance to correct its polarity. The performance outlined above will continue to take place until the rotary comes up with the correct polarity, at which time polarized relay 4 will rotate in the positive direction. The fact that polarized relay 4 definitely determines whether the conditions on the rotary are such for the balance of the operations to be carried through successfully, and if not, to bring about operation on various pieces of apparatus for correcting the fault, makes this piece of apparatus one of the most important in the whole equipment.

Shutting down the station.

After automatic reclosing circuit breaker 8 closed and picked up the station load, the position of the various parts of apparatus in the station under normal operating conditions is as follows: The oil switch on the high tension side of the transformer, and the trip coil 28 are closed, the latter being energized from the battery as explained. Operating bus switches 51 and 52, and change over switches 56, 57, and 58, are closed in the down position, time switch 1 is closed, master relay 2 is closed, starting contactor 3 is open, running contactor 6 is closed, combination automatic change over switch 5 is in running position, polarized relay 4 is in neutral position, shunt field relay 7 is closed, D. C. circuit breaker 8 is closed, reverse phase relay 23, auxiliary relay 24, reverse power relay 22, reverse current relay 20 and secondary control relay 21 are in the neutral position, as shown on print. Speed limit device 27, bearing thermostats 25, transformer thermostat 26 and sectionalizing relay 34 are in their closed position. Relay 9 is in the open position.

The station is, therefore, ready to shut down normally as follows: Time clock 1 is set beforehand to open at some certain time, and when the time arrives, the circuit between the operating coil of circuit breaker 8 and ground is broken between N¹⁹ and N²⁰, and the breaker opens dropping the station load. The connection between A¹ and A² in the A. C. feed to master relay 2 is also opened when the clock operated, but it should be noted that the gap is shunted by the rear interlock on circuit breaker 8 and wires A¹⁰ and A¹¹, and relay 2, will not open until circuit breaker 8 has opened. This is done for two reasons, namely, to keep the rotary supplied with power from the A. C. side until the D. C. power is cut off, thereby making it impossible for the rotary to run away, and also to drop the station load on the D. C. breaker instead of on the A. C. running contactor 6, as the carbon arcing tips on the former are in better position to take the arc than the copper fingers of the latter. When circuit breaker 8 opens in normal operation of the station, due to heavy overload, master relay 2 is prevented from opening due to the interlock on breaker being shunted by upper switch in time clock. When master relay 2 opens, its fingers open circuits to various apparatus as follows: fingers 2 opened the control circuit to operating coil of running contactor 6, causing same to open and thereby cutting off the A. C. supply from rotary, causing same to slow down. Finger 3 opened the ground circuit to automatic reclosing circuit breaker 8, which circuit has already been interrupted in the time clock, and which is also interrupted when interlock on running contactor 6 opens. Finger 4 of master relay 2 places another open circuit in the control circuit to operating coil of master relay 2, which open circuit is bridged when finger G of combination switch 5 moves back when latter switch opens, thereby insuring that switch 5 is in its normal starting position before master relay 2 can close again. Inasmuch as the operating coil of automatic change over switch 5 is supplied with power from the positive operating bus P through self-holding in finger D, the switch will stay closed until the rotary has slowed down to the point where there is not sufficient power to

hold the switch closed with resistance 5^r in series with the coil (approximately 100 volts) at which time the switch opens and all of the different fingers on same return to the normal or starting position. As already explained, in the description of the detail of construction of combination switch 5, finger D was the first finger to make contact when the switch closed, and, vice versa, is the last one to open when the switch opens, and finger E, which makes a shunt circuit around resistance 5^r, which is in series with the operating coil of switch 5, therefore opens ahead of finger D, and it is evident that if no other open circuit were provided in this shunt circuit that switch 5 would immediately close again due to its resistance being cut out. Finger E would then open again causing switch to open again, and the switch would continue to open and close until the voltage of the rotary had decreased to a point where the switch would not have sufficient power to operate, even though the resistance were cut out. This condition is remedied, however, by finger 5 of master relay 2, which keeps the shunt circuit around resistance 5^r open until master relay 2 closes in its regular sequence of operation. The opening of combination switch 5, transfers the shunt field from full strength supplied by the rotary itself to one-tenth full field supplied by the station bus. The fact that combination change over switch 5 stays closed till the rotary has slowed down, reduces the strength of the field considerably, and what little flux is left is dissipated through the field discharge resistance through finger C, as fingers A and B moved from the upper to the lower contact clips. The safe discharge of the shunt field is further guaranteed by the addition of time limit to the core of the operating coil of combination switch 5, which causes the latter to open very slowly. This will prevent the field from discharging very quickly in case switch 5 should open while rotary was in full service and having full strength field current. Relay 7 also dropped as the field was discharged. When switch 5 opened, finger F opened, thereby transferring the A. C. control circuit from running contactor 6 to starting contactor 3. The station is now shut down, all different parts of the apparatus are in their position for starting the rotary again. In case it is desired to have the rotary continue in operation after the time at which the clock operates, remote control relay 10 is closed before the clock has operated and is kept closed until the rotary is to be shut down, the circuits being kept closed by means of the interlocks of the remote control relay, which interlocks are connected in parallel with the interlocks on the clock. In case the station is controlled entirely by means of the remote control relay

the rotary will of course be shut down by means of this relay. In all of the above mentioned methods for shutting down the rotary, in case it is desired to continue the rotary in operation if the load carried by same is very great, low current relay 20 will prevent the rotary from shutting down, as its interlocks shunt the interlocks on time clock #1 and remote control relay #10.

Function and operation of the various protective devices in case of trouble.

I will now describe in detail the theory and operation of the various protective devices in handling any trouble that might occur either inside or outside of the station. I have already briefly described these devices in a general way, but certain specific features should also be understood, as follows:

Machine breakers, 8.—This breaker, which is an automatic reclosing circuit breaker, differs from the feeder circuit breakers 33 in that, in case the former opens at the same time as any of the feeder breakers, due, for instance, to a very severe short circuit, it will reclose again after its time limit switch has closed, regardless of conditions on the feeder, whereas the feeder breakers stay open until the trouble on the feeder has been cleared up. If, however, there is one feeder only in the station it would only be necessary to use one feeder type of circuit breaker which would act both as generator breaker and feeder breaker. When main breaker 8 opens, its front interlocks close the circuit to the operating coil of self-correcting relay 9, and if the breaker has opened due to overload it will reclose again in a few seconds, and relay 9 will drop down again. If, however, the breaker opened due to some trouble in the control wiring of the breaker, such as poor contact on one of the various interlocks in series with the operating coil of the breaker, and did not close again in two minutes, self-correcting relay 9 would close its trip circuit, causing secondary control relay 21 to operate which would shut down the station. When the D. C. voltage on the rotary has dropped to twenty-five volts, relay 21 will drop and the rotary will start again, and in this way there is a possibility of overcoming the trouble caused, for instance, by poor contact in the control circuits.

Self-correcting relay 9.—This device makes it possible for the automatic equipment to start over again in its cycle of operation in case any trouble develops. Hence, it is possible for the equipment in some cases to remedy the trouble, which feature is characterized by the name "self-correcting relay".

Low current relay 20.—This instrument is a regular shunted type switchboard am-

meter to which has been added a third binding post that makes contact with a piece of platinum that has been fastened on the lower end of the ammeter needle, which needle is electrically connected to the armature coil of the meter.

When the rotary is carrying a normal load, the lower end of the pointer makes contact with the circuit leading to the holding coil of low current auxiliary relay 20^A. When the load drops down to some predetermined value, the pointer moves in the opposite direction, and the contact between the lower end of the pointer and the platinum tip is broken, causing low current auxiliary 20^A to drop its plunger and open up the shunt circuit around the interlocks of time clock #1 and remote control relay 10. Low current auxiliary relay 20^A is equipped with a time limit, so as not to respond to momentary fluctuations in current.

Secondary control relay 21.—This relay is simply a solenoid type of relay which is used as an auxiliary relay for practically every protective device in the station. It controls the opening of master control relay 2, hence, I call it the "secondary control relay". Its main use in the station is to act as an auxiliary relay to carry the heavy currents which would in time burn the delicate contacts in the tripping circuits of the various protective devices and so cause trouble. This is accomplished in a two fold way, first due to the fact that the operating coil of relay 21 is wound with a great number of turns of fine wire, and, therefore, cuts down the amount of current that is carried by the contacts in the various protective devices, and second due to the fact that this relay is equipped with a set of self-holding interlocks that form a shunt path around all the delicate contacts in the tripping circuits of the various protective devices, it is only necessary for these contacts to make the circuit, after which the relay holds itself closed and the various protective devices can return to their normal position without being called to break the circuit to secondary control relay 21, which fact eliminates all burning of the contacts. The fact that secondary control relay stays closed till the rotary has practically ceased to rotate or generate, any current materially assists in keeping other parts of the apparatus in good operating condition when they are called upon to open the circuits, such as field control, various contact clips, reversal of field in case of wrong polarity, etc., some of which points have already been touched upon in preceding parts of the report.

Reverse power relay 22.—This meter, which is a standard single phase induction wattmeter, has its current coils connected in

one phase of the low tension power circuit by means of an 80 to 1 current transformer and its potential coils across this one phase and each of the other phases. When the machine is running, in normal service the disc of this meter tends to move, but is prevented from so doing by a small stop which holds the contacts of the trip circuit open about $\frac{3}{2}$ of an inch. In case the A. C. power supply to the rotary were interrupted the machine would run as an inverted rotary supplying at least exciting current to the power transformer. The potential would still be the same, but the direction of the current would be reversed, which would cause the disc of the reverse power relay to reverse its direction of rotation, which would close the contacts on the trip circuit in the relay, causing secondary control relay 21 to lift, which in turn would open up master control relay 2, causing rotary to shut down. The fact that the gap in the trip circuit in the reverse power relay is small, makes the meter operate very quickly (approximately one second) and in case the A. C. power is restored very quickly in case of high tension trouble, it prevents the rotary from getting a severe jolt which would result due to the A. C. power on the line being out of phase with the power being generated by the rotary when the latter is running as a generator with full strength field.

Reverse phase relay 23.—This relay as already mentioned is a standard three phase reverse phase relay that has an aluminum disc that is caused to rotate by a rotating magnetic field. The meter is connected to two 370/110 volt potential transformers that are connected open delta across the three phases of the secondary leads of the power transformers. In normal services the disc of the meter is rotated to the left as shown in the drawing until contact is made with a connection that short circuits the coil and resistance of auxiliary relay 24. In case of loss of any of the three phases, the electrical torque that rotated the disc disappears and a coiled hair spring on the shaft of the meter causes the disc to rotate to the right and make contact with the right hand terminal in the meter, thereby completing a circuit to the operating coil of auxiliary relay 24, causing same to lift and open the circuit to master control relay 2, thereby shutting down the rotary. Relay 24 is simply a straight A. C. solenoid type of relay that is equipped with two interlocks, upper one of which is used to control the circuit to master control relay 2, and the lower one serving as a self-holding or shunt circuit for the right hand contact in reverse phase relay 23 in order to hold auxiliary relay 24 up until conditions are restored to normal. The control circuit for auxiliary relay 24

is as follows: from storage battery bus S through S² and resistance 24^R (b) to right hand stud of reverse phase relay, through contact finger of reverse phase relay, S³, 5 resistance 24^R. (a) S⁴, operating coil of auxiliary 24, N²³ and N²⁴ to negative operating bus. After relay 24 has operated, it is held closed by shunt circuit S⁵; lower interlock and S⁶ as explained above. When 10 conditions are restored to normal, the disc of reverse phase relay moves to the left again engaging the left hand contact stud and short circuiting the coil and resistance a of auxiliary relay 24, causing same to drop, 15 which closes the circuit to master control relay 2, causing the rotary to start up again. In case of loss of any of the phases the coiled spring alone causes the disc to rotate to the right, but in case any of the phases become 20 reversed it would not be necessary to have a spring on the shaft because the reversed phase will cause the rotating magnetic field to reverse, which of itself would be sufficient to cause the disc to reverse from its 25 normal direction of travel. This meter will not take care of a reversal of power because its operation is like that of a motor which will reverse if we reverse either the field or the armature, but which will run in the same 30 direction if both are reversed. A reversal of power is taken care of by reverse power relay 22 already described above. Reverse phase relay 23 will also shut the station 35 down if the A. C. power becomes so low that the torque of the meter is not sufficient to overcome the pull on the coiled spring. In case any of the above-mentioned troubles occur while the rotary is not running, reverse phase relay 23 will keep same from 40 starting up until the trouble has been cleared.

Bearing thermostats 25.—These thermostats are put in the bearing for the purpose of shutting down the rotary from both the 45 A. C. and D. C. sources of power, in case the bearings become overheated. The electrical part of the thermostats is connected in the common lead that runs from oil circuit strip relay 28 and the operating coil of automatic reclosing circuit breaker 8, and when the thermostat operates this common circuit is broken and the core in relay 28 drops on the release latch on oil circuit breaker operating handle, causing the oil circuit breaker 50 to open and cut off the A. C. source of supply. The circuit to the operating coil of automatic circuit breaker 8 is also broken at this time and the breaker opens shutting off the D. C. source of supply, thereby causing the rotary to shut down. When the station 55 is shut down by the thermostat it is necessary to close the oil switch by hand again before the station can be started automatically. The oil switch could be arranged to reclose automatically, but if the

station were shut down due to an overheated bearing, same should at least be inspected before the station is put back in service.

Transformer thermostats 26.—This thermostat, which is a duplicate of the ones described above, both as to construction and operation, shuts down the rotary in case the transformer becomes overheated.

Overspeed device 27.—This device, which is made in the form of a centrifugal switch, 70 is mounted on the end of the armature shaft to prevent the rotary from being damaged due to overspeed. The electrical switch part of the speed limit device is in the same circuit with the thermostats just mentioned above, and when the weights open up due to centrifugal force, the same circuits described above open up thereby shutting down the rotary. After the speed limit device has 75 operated it is necessary to reset same by hand before station can be started automatic again. In the automatic substation, however, this device is added to the rotary as an extra precaution, as the various cases 80 of trouble that would cause the rotary to run away are provided against by means of the protective devices already described in preceding parts of this report, which devices should immediately shut down the rotary before same has a chance to speed up. Both reverse current relay 20 and reverse power relay 22 would have to be out 85 of order before the speed limit device would be called on to operate.

Oil circuit breaker trip relay and oil circuit breaker operating handle 28 and 29.—When the transformer thermostat, bearing thermostat or speed limit device operate, they cause relay 28 and oil switch breaker handle 29 to open, and before the station can 90 be started automatically again it is necessary for some one to reclose the latter apparatus, as they are not made self-closing due to the fact that the station would not 95 be in safe condition to operate after any of the above trouble had taken place. The oil circuit breaker handle is also equipped with toggle tripping device that is operated by means of an overload time limit relay whenever an excessive overload occurs on the A. C. side of the rotary, in which case it is 100 also necessary to close the oil switch by hand before the station can be started again automatically. Excessive overloads on the D. C. feeders are taken care of by the feeder circuit breakers which are set to open instantaneously, whereas the A. C. relay just mentioned has a time limit which would only be 105 called on to operate in case of burnout on the machine itself, or in case all of the feeders become overloaded simultaneously, which is 110 very rare.

Reverse current relay 30 on main breaker.—This relay which is mounted on the main 115 stud of the automatic reclosing circuit

breaker 8 is equipped with a movable contact that is in the operating circuit of automatic reclosing circuit breaker 8. The coil that closes the contact finger is connected between the main positive cable of the rotary and ground. When field circuit time limit relay 7 is not energized, it shunts a portion of the resistance that is in series with the reverse current relay coil which causes the latter relay to close, and when field circuit relay 7 operates, it removes the shunt around a portion of the resistance and the current flowing in the coil of the relay is barely sufficient to keep its contact closed. When the current in the main circuit of the circuit breaker 8 reverses, the induced field in the reverse current relay opposes the magnetism set up by the coil in the relay, causing the plunger of the relay to drop, and thus opening the circuit to the operating coil of circuit breaker 8.

Automatic reclosing feeder circuit breakers, 33.—Inasmuch as these breakers are capable of taking care of any trouble that might arise on the feeders they go a long way in helping the automatic equipment give the perfect operation that has been obtained. The following statement is a summary of the various causes of trouble that might arise in connection with the operation of an automatic substation and also shows the different protective devices that will function in each instance.

35 1st. One phase of A. C. supply line being opened during time of normal shut down; apparatus functioning if machine attempts to start up is reverse phase relay 23, which opens auxiliary relay 24, which in turn prevents master relay 2 from closing.

40 2nd. One phase of A. C. supply line being opened during time machine is running, the following apparatus functioning: reverse phase relay 23 which opens auxiliary relay 24, which in turn opens master relay 2.

45 3rd. Phase rotation of A. C. supply becoming reversed either while machine is running or during time of shutdown, the following apparatus functioning: reverse phase relay 23, opening auxiliary relay 24, which in turn opens master control relay 2 if machine is in operation, or prevents same from closing if machine was not in operation.

50 4th. Abnormally low voltage on A. C. supply either while machine is running or during time that station is shut down, the following apparatus functioning: reverse phase relay 23, opening auxiliary relay 24, which in turn opens master control relay 2 if machine is in operation, or prevents same from closing if machine was not in operation.

55 5th. A. C. supply being momentarily interrupted while machine is running carrying D. C. load, the following apparatus functioning: reverse current relay 20 and reverse power relay 22, operating secondary control relay 21, which in turn opens master control relay 2.

60 6th. A. C. supply being momentarily interrupted while machine is running, but before D. C. machine breaker 8 has closed, the following apparatus functioning: reverse power relay 22, operating secondary control relay 21, which in turn opens master control relay 2.

65 7th. A. C. supply being interrupted during time of shutdown, apparatus functioning: Due to lack of 3 phase pressure, reverse phase relay 23 will open auxiliary relay 24, which in turn will prevent relay 2 from closing. These relays will remain open until 3 phase power of correct phase rotation and potential is again available on the high tension line.

70 8th. D. C. overload on rotary converter, apparatus functioning: D. C. automatic circuit breaker 8 and D. C. automatic feeder circuit breakers 33.

75 9th. Rotary converter attempting to run at dangerous speed, apparatus functioning: Speed limit relay 27, opening sectionalizing relay 34, oil switch 29, relay 28 and D. C. rotary circuit breaker 8.

80 10th. Rotary converter attempting to build up and pick up D. C. load while polarity is reversed, apparatus functioning: Polarized relay 4, operating secondary control relay 21, which in turn opens master control relay 2.

85 11th. Reversal of polarity of rotary while carrying D. C. load due to disturbance of A. C. supply, apparatus functioning: Reverse current relay 20, operating secondary control relay 21, which in turn opens master control relay 2.

90 12th. Dirt and dust accumulating in any of the contacts of apparatus causing same to fail to make proper contacts, apparatus functioning: Relay 9, operating secondary control relay 21, which in turn opens master control relay 2.

95 13th. Momentary interruption of A. C. supply while machine is running from A. C. side, but before D. C. circuit breaker 8 has closed, the following apparatus functioning: Reverse power relay 22, operating secondary control relay 21, which in turn opens master control relay 2.

100 14th. Temperature of power transformer rising above safe value, apparatus functioning: Transformer thermostat opening sectionalizing relay 34, oil switch 29, relay 28 and D. C. circuit breaker 8.

105 15th. Rotary converter bearings rising to an abnormal temperature, following appa-

tus functioning: Bearing thermostat 25, of automatic reclosing circuit breakers 33 opening sectionalizing relay 34, oil switch on feeders. 29, relay 28 and D. C. circuit breaker 8. (2) Overheated bearings by means of

29, relay 28 and D. C. circuit breaker 8. (2) Overheated bearings by means of thermostats 25.

16th. Overload of A. C. supply, following apparatus functioning: Overload relay 5 on switch 29, opening switch 29, which in turn opens relay 28 and D. C. circuit breaker 8. (3) Overheated transformer by means of 70 thermostat 26.

17th. Open circuit in shunteld, following apparatus functioning: Shunt field relay 7 and D. C. circuit breaker 8. (4) Reverse current by means of reverse

current relay 30. (5) Overspeed by means of overspeed device 27.

18th. D. C. overload on rotary by means of automatic reclosing circuit breaker 8. (6) Extreme A. C. overload by means of

overload time limit relays. 75

From the foregoing, it may be seen that the apparatus described is a simplified form of equipment for the automatic starting, running and shutting down of light, power and railway substations. It will be observed that with this apparatus, I duplicate the simple operations that a substation attendant would perform when starting up the station, and yet I have the apparatus so arranged that each operation will have been carried through successfully before the next one can take place, and also I have the apparatus protected by means of various devices so that no matter what trouble may arise the equipment is capable of taking care of itself. This having been accomplished, the operation of the automatically controlled substation is safer and more reliable than a manually operated substation. The similarity between manual operation and automatic operation is as follows. The contact making time clock 1 is set to start the station at some predetermined time, and when it operates, then the master control relay closes the switch that starts the rotary. This switching is done on the low tension side of the transformer instead of on the high tension side as is the case with a manually operated station. When the rotary comes up to synchronous speed, polarized relay 4 determines whether the polarity is correct or incorrect, and if the latter is the case it takes the necessary steps to correct same, which corresponds to the operator correcting the polarity by using field break up switch 61. When the polarity is correct polarized relay 4 closes the combination switch 5, which in turn connects the field to the rotary lead and also changes the rotary from the half tap to the full tap on the transformer. This, in the case of a manually operated substation is done by throwing hand operated switch 60 from the starting position to the running position. In the automatic substation the field rheostat is set beforehand to give a certain voltage on the machine, and if the field has come up to the proper value for the safe operation of the rotary field circuit, time limit relay 7 closes, thereby completing the circuit to automatic reclosing circuit breaker 8, 80

Semi-automatic operation of the substation.

In case any of the automatic control apparatus should get out of order to such an extent as to make immediate repairs impossible, the apparatus has been so arranged

by means of throw over switches, etc., as to enable an inspector to start the rotary and let it run by itself until shut down by means of a clock or remote control relay, and at the same time be protected with various devices that would prevent the equipment from being damaged in case of trouble.

25 This is accomplished as follows: Change over switches 56, 57 and 58 are thrown upward, thereby cutting in that portion of the automatic equipment that is to be for manual operation, and A. C. operating bus switch 51 and D. C. operating bus switch 52 are opened, thereby shutting off the power, both A. C. and D. C. from that portion of the apparatus that is not to be used in the manual operation of the station. 35 Shunt field break up switch 61 is also opened.

The method of operation is then as follows: Contact making time clock 1, or remote control relay 10, and oil circuit breaker handle 29 are closed and the cores in oil circuit breaker trip relay 28 and sectionalizing relay 34 are lifted. Hand operated starting switch 60 is thrown to the "half tap" position and the rotary starts up and falls into step with the frequency on the high tension line. If the rotary should come up with the wrong polarity, the oil switch is opened and the rotary is allowed to slow down after which the oil switch is closed again, thereby causing the rotary to slip a pole and correct its polarity. When the polarity has come up correct, field break up switch 61 is closed, and hand operated starting switch 60 is thrown to the full voltage or running position. The rotary is now up to full voltage and correct polarity, and by closing a small control switch, automatic reclosing circuit breaker 8 is made to close thereby picking up the station load. The station is now in regular service and if no trouble occurs, it will continue until shut down by means of time clock or remote control relay. The rotary is protected against various trouble as follows:

35 (1) Overload on D. C. feeders by means

of automatic reclosing circuit breaker 8. (6) D. C. overload on rotary by means of automatic reclosing circuit breaker 8.

(7) Extreme A. C. overload by means of

overload time limit relays. 75

80 From the foregoing, it may be seen that the apparatus described is a simplified form of equipment for the automatic starting, running and shutting down of light, power and railway substations. It will be observed that with this apparatus, I duplicate the simple operations that a substation attendant would perform when starting up the station, and yet I have the apparatus so arranged that each operation will have been carried through successfully before the next one can take place, and also I have the apparatus protected by means of various devices so that no matter what trouble may arise the equipment is capable of taking care of itself. This having been accomplished, the operation of the automatically controlled substation is safer and more reliable than a manually operated substation. The similarity between manual operation and automatic operation is as follows. The contact making time clock 1 is set to start the station at some predetermined time, and when it operates, then the master control relay closes the switch that starts the rotary. This switching is done on the low tension side of the transformer instead of on the high tension side as is the case with a manually operated station. When the rotary comes up to synchronous speed, polarized relay 4 determines whether the polarity is correct or incorrect, and if the latter is the case it takes the necessary steps to correct same, which corresponds to the operator correcting the polarity by using field break up switch 61. When the polarity is correct polarized relay 4 closes the combination switch 5, which in turn connects the field to the rotary lead and also changes the rotary from the half tap to the full tap on the transformer. This, in the case of a manually operated substation is done by throwing hand operated switch 60 from the starting position to the running position. In the automatic substation the field rheostat is set beforehand to give a certain voltage on the machine, and if the field has come up to the proper value for the safe operation of the rotary field circuit, time limit relay 7 closes, thereby completing the circuit to automatic reclosing circuit breaker 8, 85

90

130

which closes, picking up the station load. In the manually operated substation the field rheostat is set by the operator after he has started up the machine, and if the voltmeter shows that the voltage on the rotary is at the correct value he closes the main circuit breaker and switch thereby picking up the station load. Thus it may be seen that the operations made by the automatic 10 substation apparatus in the starting, running and shutting down of the station are practically identical with those of an operator, and due to the simplicity of the few parts that are used there can only be great 15 reliability of service and a minimum amount of cost for maintenance.

As may be seen from the description of the method of operation in starting up, running and shutting down the substation, it 20 is evident that the automatic equipment is so arranged that each piece of apparatus is so interlocked electrically or mechanically that each and every part of the equipment must be and is in its correct position, such 25 as will enable the station to start up, operate and shut down without any damage to any part of the equipment. In this respect the automatic equipment described in this report is superior to that of a substation attendant, as cases are on record where operators have endeavored to start up substations with some of the switches or other devices being in the incorrect position, which in some cases resulted in serious injury to 30 both the attendant and the equipment, and also caused an interruption to the service. Instances have also happened where an operator has opened switches on machines in operation instead of on the one being shut 35 down, which has resulted in serious interruption to the service, and in some instances damage to the equipment and the attendant. With my improved equipment I positively avoid such accidents.

40 Although but one specific embodiment of this invention has been herein shown and described it will be understood that numerous details of the construction shown may be altered or omitted without departing 45 from the spirit of this invention as defined by the following claims.

I claim:

1. In an automatic electric power substation a rotary converter, a time member (1), 50 automatic means (3 and 6) responsive to said time member (1) for starting said converter, automatic means (8) responsive to the normal operation of the station to connect said converter to said direct current 55 distribution circuit, automatic means (9) responsive subject to a time limit to stop said converter in case of abnormal conditions, and means (21) responsive to said means (9) to successively restart said converter until normal conditions prevail.

2. An alternating current supply circuit, a direct current distribution circuit, a rotary converter, a polarized relay oppositely responsive electrically according to the polarity of said converter, means controlled by 70 said relay to cause repeated starting of said converter until it comes up with proper polarity, and means controlled by said relay to then connect said converter to said distribution system. 75

3. In a rotary converter substation, automatic control means including a polarized relay, means controlled thereby to disconnect the converter from its supply circuit when its polarity comes up wrong, and means controlled by said relay to connect said converter to the distribution circuit when the polarity comes up right. 80

4. In a system of the character described, an A. C. supply circuit, a rotary converter, a remote control relay, pilot wires extending from said pilot relay to any desired remote point of control, and a D. C. distribution circuit, which relay is controlled by current sent from said remote point by means of said pilot wires, and means responsive to said relay to start said rotary converter and connect same to said distribution circuit when said converter has correct polarity, and means to disconnect said rotary converter when power is no longer needed. 90 95

5. In a system of the character described, an A. C. supply circuit, a rotary converter and a D. C. distribution circuit, in combination with a chosen means to start said converter, and means responsive to the polarity of the converter to successively stop and restart same until it comes up with a chosen predetermined polarity, and then connect it to said distribution circuit. 100 105

6. In an electric power substation, in combination, a supply circuit, a rotary converter, a distribution circuit, manually operated control means for starting said converter, automatic means, responsive to abnormal conditions, for shutting down the converter and automatic means, responsive to remote control, for shutting down the converter. 110

7. In an electric power substation, in combination, a supply circuit, a rotary converter, a distribution circuit, manually controlled means for starting the converter, automatic means, responsive to abnormal conditions, for shutting down the rotary converter, and automatic means responsive to time for shutting down the converter. 115

8. In an automatic electric power substation, a rotary converter having shunt field windings, means to connect said windings to an external source of direct current, automatic means for starting said converter, automatic means for establishing running connections for said converter, polarity controlled means responsive to the direct cur- 120 125 130

- rent polarity of said converter, and a combination automatic field control and change-over switch responsive to said polarity controlled means, said switch having arms 5 adapted to change the field excitation of said converter from separate excitation by said external source of self excitation, and also to open the starting means and close the running connection establishing means.
- 10 9. In an automatic electric power substation, an alternating current supply circuit, a direct current distribution circuit, a rotary converter, a time member (1), automatic means (3 and 6) responsive to said time member (1) for starting said converter, automatic means (8) responsive to the normal operation of the station to connect said converter to said direct current distribution circuit and automatic means (9) responsive 15 to abnormal conditions and subject to time to stop said converter in case of abnormal conditions and means (21) responsive to one of said means (9) to successively restart said converter until normal conditions prevail.
- 15 10. In an automatic electric power substation, an alternating current supply circuit, a direct current distribution circuit, a rotary converter, a time member (1), automatic means (3 and 6) responsive to said time member (1) for starting said converter and automatic means (9) responsive to abnormal conditions and subject to time to stop said converter in case of abnormal conditions 20 while converter is being started and means (21) responsive to said means (9) to successively restart said converter until normal conditions prevail.
- 20 11. In an automatic electric power substation, an alternating current supply circuit, a direct current distribution circuit, a rotary converter a time member (1), automatic means (3 and 6) responsive to said time member (1) for starting said converter and automatic means (9) responsive to abnormal conditions and subject to time to stop said converter in case of abnormal conditions while converter is being started and means (21) responsive to said means (9) to 25 successively restart said converter until normal conditions prevail, and automatic means (8) responsive to the normal operation of the converter to connect said converter to said direct current distribution circuit.
- 25 12. In an automatic electric power substation having an alternating current supply circuit and a direct current distribution circuit, a rotary converter having shunt field windings, means to connect said windings to an external source of direct current, automatic means for starting said converter, automatic means for establishing running connections for said converter, polarity controlled means responsive to the direct cur-
- rent polarity of said converter, a combination automatic field control and change-over switch responsive to said polarity controlled means, said switch having arms adapted to change the field excitation of said converter from separate excitation by said external source to self excitation, and also to open the starting means and close the running-connection establishing means, and means responsive to the closure of said running-connection establishing means for the connecting said converter to said direct current distribution circuit.
- 30 13. In an automatic electric substation, an alternating current supply circuit, a direct current distribution circuit, a rotary converter having shunt field windings, means to connect said windings to an external source of direct current, automatic means for starting said converter, automatic means for establishing running connections 35 for said converter, polarity controlled means responsive to the direct current polarity of said converter, and means responsive to said polarity controlled means for changing the excitation of said converter from said external source of direct current to self excitation from said converter.
- 35 14. In a system of the character described, an A. C. supply circuit, a rotary converter and a D. C. distribution circuit, in combination with means responsive to time, and to the D. C. potential of said distribution circuit to start said converter and connect it to said distribution circuit.
- 40 15. In a system of the character described, an A. C. supply circuit, a rotary converter, a D. C. distribution circuit, a time member, a voltage relay connected to said distribution circuit, automatic means responsive to said time member, and subject to operation of said relay on a predetermined minimum voltage on said distribution system, to start said converter and connect same to said distribution circuit and means responsive to a time member to shut converter down at a predetermined time.
- 45 16. In an automatic electric substation, an A. C. supply circuit, a D. C. distribution circuit, a rotary converter, a time member (1), a low voltage relay connected to said D. C. distribution circuit and arranged to operate on a certain predetermined minimum value of potential on said distribution circuit, automatic means (3 and 6), responsive to said time member (1) and subject to operation of said voltage relay (11), for starting said converter, automatic means (8), responsive to the normal operation of said converter, to connect said converter to said direct current distribution circuit, automatic means (9) responsive, subject to a time limit, to stop said converter in case of abnormal conditions and means (21) re-

sponsive to said means (9), to successively restart said converter until normal conditions prevail.

17. In an automatic electric power substation a rotary converter, a time member (1), automatic means (3 and 6) responsive to said time member (1) for starting said converter, automatic means (8) responsive to the normal operation of the converter to connect said converter to said distribution circuit, automatic means responsive to time member (1) to shut station down at a predetermined time.

18. In an automatic electric substation, an A. C. supply circuit, a D. C. distribution circuit, a rotary converter, a time member (1), a low voltage relay (11) connected to said distribution circuit and arranged to operate on a certain predetermined minimum value of potential on said distribution circuit, automatic means (3 and 6), responsive to said time member (1) and subject to operation of said voltage relay (11), to start said converter, automatic means (8), responsive to the normal operation of the converter and its auxiliary equipment, to connect said converter to said distribution circuit, and automatic means, responsive to time member (1), to shut converter down at a predetermined time.

19. In an automatic electric substation, an A. C. supply circuit, a D. C. distribution circuit, a rotary converter, a time member, a low voltage relay connected to said distribution circuit and arranged to operate on a certain predetermined minimum value of potential on said distribution circuit, and a minimum current relay connected in the main circuit of said converter and arranged to operate on a certain predetermined value of load on said converter, automatic means, responsive to said time member, subject however, to operation of said low voltage relay, to start said converter, and automatic means to connect said converter to said distribution circuit and automatic means, responsive to said time member, subject however to operation of said minimum current relay, to shut down said converter.

20. In an automatic electric power substation, in combination, a supply circuit, a rotary converter, a distribution circuit, a time member, a minimum current relay connected in the main circuit of said converter and arranged to operate on a certain predetermined minimum value of load on said converter, manually controlled means for starting said converter, automatic means, responsive to abnormal conditions, for shutting down said converter, and automatic means responsive to said time member, subject however to operation of said minimum current relay, to shut down said converter.

21. In an electric power substation, in

combination, a supply circuit, a rotary converter, a distribution circuit, a remote control relay, a time member, manually controlled means for starting the converter, automatic means responsive to abnormal conditions for shutting down the converter and automatic means responsive to said time member for shutting down the converter at a certain predetermined time, said means however being also responsive to said remote control relay which can cause the converter to continue to operate as long as desired after said time member has functioned.

22. In a system of the character described, a rotary converter, a time member and a remote control relay, means, responsive to said time member, to automatically start and stop said converter at a certain predetermined time, and means, responsive to said remote control relay, to start and stop said converter at some time other than said predetermined time, should necessity arise.

23. In an automatic electric substation, an A. C. supply circuit, a D. C. distribution circuit, a rotary converter, a time member, a low voltage relay connected to said distribution circuit and arranged to operate on a certain predetermined minimum value of potential on said distribution circuit, and a remote control relay, automatic means, responsive to said time member and subject to operation of said voltage relay, to start said converter after a certain predetermined time, and means, responsive to said time member, to stop said converter after a certain predetermined time and means, responsive to said remote control relay, to start and stop converter at some time other than said time, should necessity for same arise.

24. In an automatic electric substation, an A. C. supply circuit, a D. C. distribution circuit, a rotary converter, a time member, a low voltage relay connected to said distribution circuit and arranged to operate on a certain predetermined minimum value of potential on said distribution circuit, a minimum current relay connected in the main circuit of said converter and arranged to operate on a certain predetermined value of load on said converter, and a remote control relay, automatic means responsive to said time member, subject however to operation of said low voltage relay, to start said converter, automatic means to connect said converter to said distribution circuit, and automatic means, responsive to said time member, subject however to operation of said minimum current relay, to shut down said converter and means, responsive to said remote control relay, to start and stop said converter at some time, other than said time, should necessity for same arise.

25. In an automatic electric substation,

- an A. C. supply circuit, a D. C. distribution circuit, a rotary converter, a time member, a remote control relay, automatic means responsive to said time member to start said converter from said A. C. supply circuit at a predetermined time, means for obtaining a certain predetermined polarity at the direct current end of said converter, means, responsive to said predetermined polarity, to connect said converter to said distribution circuit, and means, responsive to said time member, to shut down said converter at a certain predetermined time, and means, responsive to said remote control relay to start and stop said converter at a time, other than said predetermined time, should necessity for same arise.

26. In an automatic electric power substation, an A. C. supply circuit, a rotary converter, a D. C. distribution circuit, automatic means (3 and 6) for connecting the converter to the A. C. supply circuit under predetermined voltage conditions on said distribution circuit, a polarized relay opposite responsive electrically, according to the polarity of said converter, means controlled by said relay to cause repeated starting of said converter until it comes up with proper polarity and means controlled by said relay to then connect said converter to said distribution circuit.

27. In an automatic electric substation, an A. C. supply circuit, a rotary converter, a D. C. distribution circuit, automatic means responsive to a certain electrical condition of said distribution circuit to start said rotary from said supply circuit, control means including a polarized relay, means controlled thereby to disconnect the converter from its supply circuit when its polarity comes up wrong, and means controlled by said relay to connect said converter to the distribution circuit when the polarity comes up right.

28. In an automatic electric substation, an A. C. supply circuit, a D. C. distribution circuit, a rotary converter, a time member, automatic means for connecting said converter to said supply circuit under predetermined voltage conditions on said distribution circuit, a polarized relay oppositely responsive electrically, according to the polarity of said converter, means controlled by said relay to cause repeated starting of said converter until it comes up with proper polarity, means controlled by said relay to then connect said converter to said distribution circuit, and means, responsive to said time member, to shut down said converter at a predetermined time.

29. In an automatic electric substation, an A. C. supply circuit, a D. C. distribution circuit, a rotary converter, a remote control relay, automatic means for connecting said converter to said supply circuit under predetermined voltage conditions on said distribution circuit, a polarized relay oppositely responsive electrically, according to the polarity of said converter, means controlled by said relay to cause repeated starting of said converter until it comes up with proper polarity, means controlled by said relay to then connect said converter to said distribution circuit, and means, responsive to said time member, to shut down said converter at a predetermined time.

30. In an automatic electric substation, an A. C. supply circuit, a D. C. distribution circuit, a rotary converter, a minimum current limit relay connected in the main circuit of said converter and arranged to operate on a predetermined minimum value of load on said converter for a definite period of time, automatic means for connecting said converter to said supply circuit under predetermined voltage conditions on said distribution circuit, a polarized relay oppositely responsive electrically according to the polarity of said converter, means controlled by said relay to cause repeated starting of said converter until it comes up with proper polarity, means controlled by said relay to then connect said converter to said distribution circuit and means, responsive to operation of said minimum current relay, to shut down said converter.

31. In an automatic electric substation an A. C. supply circuit, a D. C. distribution circuit, a rotary converter, a time member, a remote control relay, automatic means for connecting said converter to said supply circuit under predetermined voltage conditions on said distribution circuit, a polarized relay oppositely responsive electrically according to the polarity of said converter, means controlled by said relay to cause repeated starting of said converter until it comes up with proper polarity and means controlled by said relay to then connect said converter to said distribution circuit, means responsive to said time member, to shut down said converter at a predetermined time, and means, responsive to said remote control relay, to shut down said converter at some time, other than said time, should necessity for same arise.

32. In an automatic electric substation, an A. C. supply circuit, a D. C. distribution circuit, a rotary converter, a time member, a minimum current time limit relay connected in the main circuit of said converter and arranged to operate on a certain predetermined value of load on said converter for a definite period of time, a remote control relay, automatic means for connecting said converter to said supply circuit under predetermined voltage conditions on said distribution circuit, a polarized relay oppositely responsive electrically, according to the polarity of said converter, means controlled by said relay to cause repeated starting of said converter until it comes up with proper polarity, means controlled by said relay to then connect said converter to said distribution circuit and means, responsive to operation of said minimum current relay, to shut down said converter.

- 5 polarity of said converter, means controlled by said polarized relay to cause repeated starting of said converter until it comes up with proper polarity, means controlled by 65
 5 said polarized relay to then connect said converter to said distribution circuit, means, responsive to said time member subject however to operation of said minimum current relay, to shut down said converter after a 70
 19 predetermined time and means, responsive to said remote control relay, to shut down said converter at some time other than said time, should necessity arise.
33. In an automatic electric substation, an 15 A. C. supply circuit, a D. C. distribution circuit, a rotary converter, a minimum current time limit relay, connected in the main circuit of said converter and arranged to operate on a predetermined minimum value 80
 20 of load on said converter for a definite period of time, a remote control relay, automatic means for connecting said converter to said supply circuit under predetermined voltage conditions on said distribution circuit, a polarized relay oppositely responsive electrically according to the polarity of said converter, means controlled by 85
 25 said relay to cause repeated starting of said converter until it comes up with correct polarity, means controlled by said relay to then connect said converter to said distribution circuit, means, responsive to operation of said minimum current relay, to shut down said converter when load on same 90
 30 reaches a certain minimum value, and means, responsive to said remote control relay, to shut down converter at some time other than said time of minimum load.
34. In an automatic electric substation, an 40 A. C. supply circuit, a D. C. distribution circuit, a rotary converter, a time member, automatic means responsive to a certain electrical condition of said distribution circuit to start said rotary from said supply circuit, control means including a polarized relay, means controlled thereby to disconnect the converter from its supply circuit when its polarity comes up wrong, means controlled by 95
 45 said relay to connect said converter to the distribution circuit when the polarity comes up right and means, responsive to said time member, to shut down converter at a predetermined time. 100
 50
35. In an automatic electric substation, an 55 A. C. supply circuit, a D. C. distribution circuit, a rotary converter, a remote control relay, automatic means, responsive to a certain electrical condition of said distribution circuit, to start said converter from said supply circuit, control means including a polarized relay, means controlled thereby to disconnect the converter from its supply circuit when its polarity comes up wrong, means controlled by 105
 60 said relay to connect said converter to the distribution circuit when the polarity come up right, means, responsive to said time member, subject however to operation of said minimum current relay, to shut down said converter after a predetermined time and means, responsive to said remote 110

- said converter to said distribution circuit 65 when the polarity comes up right and means, responsive to said remote control relay, to shut down said converter.
36. In an automatic electric substation, an 70 A. C. supply circuit, a D. C. distribution circuit, a rotary converter, a minimum current time limit relay connected in the main circuit of said converter and arranged to operate on a predetermined minimum value of current for a definite period of time, automatic means, responsive to a certain electrical condition of said distribution circuit, to start said converter from said supply circuit, control means including a polarized relay, means controlled thereby to disconnect the converter from its supply circuit when its polarity comes up wrong, means controlled by 75
 80 said relay to connect said converter to said distribution circuit when the polarity comes up right, and means, responsive to operation of said minimum current relay, to shut down said converter.
37. In an automatic electric substation, an 85 A. C. supply circuit, a D. C. distribution circuit, a rotary converter, a time member, a remote control relay, automatic means, responsive to a certain electrical condition of said distribution circuit, to start said converter from said supply circuit, control means including a polarized relay, means controlled thereby to disconnect the converter from its supply circuit when its polarity comes up wrong, means controlled by 90
 95 said relay to connect said converter to said distribution circuit when the polarity comes up right, means, responsive to said time member, to shut down said converter at a predetermined time, and means, responsive to said remote control relay, to shut down said converter at some time other than said 100
 105 time, should necessity for same arise.
38. In an automatic electric power substation, an A. C. supply circuit, a rotary converter, a time member, a minimum current time limit relay connected in the main 110 circuit of said converter and arranged to operate on a certain predetermined value of load on said converter for a definite period of time, a remote control relay, automatic means, responsive to a certain electrical condition of said distribution circuit, to start said converter from said A. C. supply circuit, control means including a polarized relay, means controlled thereby to disconnect said converter from said supply circuit when its polarity comes up wrong, means controlled by 115
 120 said relay to connect said converter to said distribution circuit when the polarity come up right, means, responsive to said time member, subject however to operation of said minimum current relay, to shut down said converter after a predetermined time and means, responsive to said remote 125

control relay, to shut down said converter at some time other than said time should necessity arise.

39. In an automatic electric substation, an A. C. supply circuit, a D. C. distribution circuit, a rotary converter, a minimum current time limit relay connected in the main circuit of said converter and arranged to operate on a predetermined minimum value of load on said converter for a definite period of time, a remote control relay, automatic means, responsive to a certain electrical condition of said distribution circuit, to start said converter from said A. C. supply circuit, means controlled thereby to disconnect

said converter from said supply circuit when its polarity comes up wrong, means controlled by said relay to connect said converter to said distribution circuit when the polarity comes up right, means, responsive to operation of said minimum current relay, to shut down said converter when load on same reaches a certain minimum value and means, responsive to said remote control relay, to shut down converter at some time other than at said time of minimum load.

Signed at Chicago this 22 day of June, 1921.

VICTOR E. THELIN.
